OR D 33,597 EX

DESIGN.

No. 33,597.

Patented Nov. 20, 1900.

A. M. PRICE.

FORK FOR BICYCLE OR LIKE TUBULAR FRAMES.

(Application filed Oct. 22, 1900.)

UNITED STATES PATENT OFFICE.

ALBERT M. PRICE, OF CHICAGO, ILLINOIS, ASSIGNOR TO WILLIAM H. FAUBER, OF SAME PLACE.

DESIGN FOR A FORK FOR BICYCLE OR LIKE TUBULAR FRAMES.

SPECIFICATION forming part of Design No. 33,597, dated November 20, 1900.

Application filed October 22, 1900. Serial No. 33,974. Term of patent 7 years.

To all whom it may concern:

Be it known that I, ALBERT M. PRICE, a citizen of the United States, residing at Chicago, in the county of Cook and State of Illinois, have invented and produced a new and original Design for a Fork for Bicycle or Like Tubular Frames, of which the following is a specification, reference being had to the accompanying drawings, forming part thereof.

10 In the said drawings, Figure 1 is a view in side elevation of a frame-fork embodying my novel design. Fig. 2 is an edge view thereof. Fig. 3 is a cross-section of the fork-arm, taken on line 3-3 of Fig. 1. Fig. 4 is a similar cross-section of one of the arms of the fork, taken 15 on line 4-4 of Fig. 1.

The leading or characteristic features of a bicycle-frame fork made in accordance with my design are as follows: The arms of the fork are made smaller at their outer than at their inner ends, where they are joined to each other by a connecting part or crown, and they taper from their inner to their outer ends. Both the outer and inner sides or faces of each fork-arm is composed mainly of three plane surfaces, an intermediate surface, and two lateral surfaces. The said intermediate surface is widest at the outer end of the arm and extends the full width of the arm at the 25 said outer end thereof and tapers gradually toward the inner end of the arm. At the said inner end of the arm the margins of said intermediate surface are brought together, or nearly so. The lateral oblique surfaces are

disposed symmetrically, one on each side of the intermediate surface, and are arranged obliquely to said intermediate surface. The said oblique lateral surfaces are widest at the inner end of the arm, extending at said inner end of the arm from the side edges thereof to 35 the central lines of its outer and inner faces and taper gradually toward the outer end of the arm, where the margins thereof are brought together, or nearly so. The inner side margins of each of said lateral oblique surfaces 40 meet or coincide with the side margins of the intermediate surface, so as to form two angles at either side of said intermediate surface extending the full length of each fork-arm. The side edges of each fork-arm are 45 equal in width to the thickness of the arm at the outer end thereof and taper gradually toward the inner end of the arm. The outer end of each arm is substantially rectangular in cross-section, as shown in Fig. 3, while the 50 inner end of each arm is generally of lozenge or diamond shape, as shown in Fig. 4.

What I claim as new is—

The design for a fork for bicycle and like tubular frames substantially as herein shown 55 and described.

Signed at Chicago, Illinois, on this 18th day of October, A. D. 1900.

ALBERT M. PRICE.

In presence of—

HENRY W. NORTON,
JOHN H. GLENN.
